[57] CLAIM

The ornamental design for a cosmetic kit, as shown and described.

DESCRIPTION

FIG. 1 is a front elevational view of a cosmetic kit showing my new design;

FIG. 2 is a rear elevational view;

FIG. 3 is a right side elevational view;

FIG. 4 is a left side elevational view;

FIG. 5 is a top plan view;

FIG. 6 is a bottom plan view;

FIG. 7 is a top, front and left side perspective view thereof;

FIG. 8 is a perspective view in an open condition; and,

FIG. 9 is a top plan view thereof.

The undisclosed bottoms of the makeup trays are unornamented and planar except for the appearance of the slot openings on the left and right trays.
